(Cl. D83—1)

To all whom it may concern:

Be it known that I, Matthew B. Adrian, a citizen of the United States, residing at Milwaukee, in the county of Milwaukee and State of Wisconsin, have invented a new, original, and ornamental Design for Foot X-Ray Machines, of which the following is a specification, reference being had to the accompanying drawing, forming part thereof.

Fig. 1 is a side view of the foot X-ray machine embodying my new design.

Fig. 2 is a front view thereof.

Fig. 3 is a rear view thereof.

Fig. 4 is a plan view thereof.

I claim:

The ornamental design for a foot X-ray machine, as shown.

MATTHEW B. ADRIAN.
